CLAIM

The ornamental design for a device for use with utility meters to record time of energy use, demand and load profile data, as shown.

DESCRIPTION

FIG. 1 is a front and bottom perspective view of a device for use with utility meters to record time of energy use, demand and load profile data showing our new design;

FIG. 2 is a front elevational view;

FIG. 3 is a bottom plan view;

FIG. 4 is a rear elevational view;

FIG. 5 is a top plan view;

FIG. 6 is a right side elevational view, the left side elevational view being a mirror image; and

FIG. 7 is top, front and side perspective view thereof.
